UNITED STATES PATENT OFFICE

161,909

PIANO ORGAN

Douglas Duke, Rochester, N. Y.

Application August 23, 1949, Serial No. 4,667

Term of patent 14 years

(Cl. D56—2)

To all whom it may concern:

Be it known that I, Douglas Duke, a citizen of the United States, residing at Rochester, in the county of Monroe and State of New York, have invented a new, original, and ornamental Design for a Piano Organ, of which the following is a specification, reference being had to the accompanying drawing, forming part thereof.

Figure 1 is a perspective front view of a piano organ, showing my new design;

Figure 2 is a top plan view;

Figure 3 is a side elevation looking from the right with respect to Figure 2;

Figure 4 is a side elevation looking from the left with respect to Figure 2

The rear side of the article, not shown, is substantially plain.

I claim:

The ornamental design for a piano organ, substantially as shown and described.

DOUGLAS DUKE.
